COMBINED PACKAGING CARD AND HANGER FOR AN ARTICLE OF MERCHANDISE

Charles A. Wells, Marysville, Ohio, and Robert A. O'Neil and Michael C. Wilson, Wheaton, Ill., assignors to Pretty Products, Inc., Coshocton, Ohio

Filed Nov. 25, 1974, Ser. No. 526,530

Term of patent 14 years

Int. Cl. D9—99

U.S. Cl. D9—292

FIG. 1 is a perspective view of a combined packaging card and hanger for an article of merchandise embodying our new design with an article packaged therewith and shown in broken lines for illustrative purposes only;

FIG. 2 is a front elevational view thereof; and

FIG. 3 is a top plan view thereof.

We claim:

The ornamental design for a combined packaging card and hanger for an article of merchandise, as shown and described.
